MAXIMILIAAN JULIUS OTTO STRUTT AND POPKO REINDER DIJKSTERHUIS, OF EINDHOVEN, NETHERLANDS, ASSIGNEES TO RADIO CORPORATION OF AMERICA, A CORPORATION OF DELAWARE

ARRANGEMENT FOR TRANSMITTING WIRELESS SIGNALS

Application filed September 5, 1929, Serial No. 390,526, and in the Netherlands September 1, 1928.

This invention relates to antennæ or aerials adapted to transmit wireless signals and more particularly to those having a directional effect.

5 This invention has for its object a process and an arrangement for varying at will the direction in which the signals are transmitted.

Aerial systems have been already proposed, in which the radiation in particular directions can be amplified or attenuated by using at least three aerials which, dependent upon the direction desired, can be energized in variable, mutually different phases. With these systems rather complicated devices for controlling the relative phase are required.

According to this invention, a process for varying the direction is carried out, in which a beam of electro-magnetic waves is radiated by a directional aerial system whose feeding 20 is effected in such manner that the amplitude of the oscillations in the various radiators of the system regulably increases or decreases from one side to the other, the phases in the said radiators being, however, maintained 25 mutually equal.

For carrying out this process use should preferably be made of an aerial constituted by a transmission line and two or more radiators which together with the said transmission line are located in a plane while the supply of the radiators can be effected at will with mutual difference of amplitude at one or more points of the transmission line.

Further explanation of the invention follows with reference to the accompanying drawing which represents diagrammatically, by way of example, embodiments of the invention.

Figure 1 represents an aerial to which the process according to the present invention can be applied.

Figure 2 shows another mode of arranging the conductors concluding the transmission line.

Figure 3 represents the diagram of an aerial which is fed only on one side.

As appears from Figure 1, an aerial 1 consists of a transmission line constituted by two horizontal conductors or feeders 2 which are 50 located the one above the other a half wave-

length apart and between which are arranged at distances of a half-wave-length a plurality of radiators 3 having free electrical ends and each having a length of a half wave-length. On both sides the transmission line is closed by a conductor 4 which, electrically speaking, is made twice as long as a half wave-length by means of a coil 5, the feeding being effected on both sides at one of these half wave-lengths by means of transformers 6. These transformers are supplied by leads 7 from an auto-transformer 8, which is coupled to the transmitter by means of leads 9. Variable inductances 10 are inserted in the two feeders in order to equalize the phase of the currents 65 passings through the said feeders.

It is also possible to make the conductors 4 spatially twice a half-wave length long, which is constructively still more advantageous. This is represented in Figure 2.

As the ends of each of the conductors 4 are in the same phase and the radiators 3 are connected at distances of half a wave-length alternately to the upper and the lower conductor 2, it may be obtained that all the radiators are energized in the same phase, so that a directional radiation is produced whose main direction under normal conditions is perpendicular to the plane of the aerial.

It is possible to vary this main direction of radiation in a simple manner between the definite limits by relatively varying the amplitude of the currents supplied on both sides to the aerial. This variation of amplitude can be effected by the displacement of variable tapping points 11 on the auto-transformer, the phase-coincidence of the currents supplied along the two feeders 7 being controlled with the aid of the above mentioned adjustable inductances 10.

Figure 3 represents an aerial system which is fed only on one side. In this case the desired variation of amplitude in the successive radiators is obtained owing to the fact that in each of the conductors 2 between the successive points of connection of each two radiators are connected in series, a variable resistance 12 and a variable inductance 13, the latter being destined for the phase-correction.

With this arrangement, however, the directive effect can only be influenced at the cost of extra energy-losses in the transmission line; such losses are obviated by having
5 the feeding effected at two or more points of the aerial system.

When applying the process according to the present invention to an aerial which preferably should be used for this purpose,
10 the main direction of radiation can be rotated through an angle of about 30° , which for long-distance transmission is amply sufficient.

In order to ensure a sufficient directional effect it is advisable to give the aerial a length
15 of more than one wave-length.

We claim:

1. An antenna system comprising a transmission line, electrically open ended radiators coupled thereto, an auto-transformer supplied with high frequency current, and feeders coupling each end of the transmission line to the auto-transformer.

2. An antenna system comprising a transmission line, electrically open ended radiators coupled thereto, an auto-transformer supplied with high frequency current, feeders coupling each end of the line to the auto-transformer, and phase adjusting means in
25 the feeders.

3. An antenna system comprising a pair of conductors forming a transmission line, electrically open ended radiators coupled to the transmission line, a resistor and an inductor connected in series in each of the conductors of said transmission line between successive points of connection of each pair of radiators, and means for supplying high frequency energy to the transmission line.

4. A directional transmitting antenna system comprising a two wire transmission line, open-ended aerials coupled alternately to different wires of said line, an auto-transformer supplied with high frequency current, and a connection coupling said transmission line to said auto-transformer.

5. A directional transmitting antenna system comprising a two-wire transmission line, open-ended aerials coupled alternately to different wires of said line, an auto-transformer supplied with high frequency current, and means coupling said transmission line to variable taps on said auto-transformer.
